[57] CLAIM

The ornamental design for a telescoping measuring stick, as shown and described.

DESCRIPTION

FIG. 1 is a left front perspective view of a telescoping measuring stick showing my new design, showing the measuring arm in the extended position;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof;

FIG. 7 is a bottom plan view thereof;

FIG. 8 is a front elevational view thereof with the measuring arm in a folded position.

FIG. 1.

FIG. 2.

FIG. 3

FIG. 4

FIG. 5.

FIG. 6.

FIG. 7.

FIG. 8.
